UNITED STATES PATENT OFFICE.

CHARLES C. BRIAND, OF REVERE, MASSACHUSETTS, ASSIGNOR TO PETER GRAY & SONS,
A CORPORATION OF MASSACHUSETTS.

LANTERN OR LAMP.

1,022,821.

Specification of Letters Patent.

Patented Apr. 9, 1912.

Application filed October 8, 1908. Serial No. 456,833.

To all whom it may concern:

Be it known that I, CHARLES C. BRIAND, a citizen of the United States, residing in Revere, county of Suffolk, Commonwealth of Massachusetts, have invented certain new and useful Improvements in Lanterns or Lamps, of which the following is a specification, reference being had to the drawings accompanying the same and forming a part 10 thereof.

My invention relates to lanterns or lamps.

The object of my invention is to provide means for supplying air to the burner or flame of a lantern or lamp from the top 15 to promote proper combustion.

A further object of my invention is to provide means to shield the flame of the burner from strong currents or gusts of air, thus to prevent the flame from flickering or from 20 being extinguished.

In the drawings which accompany this specification and form a part thereof the figure is a sectional elevation of the lantern showing the construction of my top draft 25 device.

The body 1 of the lantern is provided with a base 2 which is designed to support a reservoir 3 of the burner 4. The sides of the body of the lantern or lamp may have 30 inserted therein one or more lenses 5, the lenses being held in the usual manner. The reservoir 3 and burner 4 are removed through a sliding door 6 which slides upwardly on runways of the usual type in such lanterns.

The top of the lantern is composed of the irregular cone-shaped cover 7 which is part of or may be secured to the body of the lantern 1. The top is provided with an inwardly curving flange portion 8, the purpose of which will be more fully explained hereafter. A hinge-top 9 is pivoted to the portion 7 by any suitable form of hinge, and it may be provided with a suitable catch 10 to hold it in its closed position. The 45 cone-shaped portion 9 has an inturned edge 11 which is provided with a series of holes 12, 12, etc., to permit the air to escape upwardly. It has a central opening of a size to inclose the cone 13. The cone 13 has attached to its lower end by rivets or otherwise a perforated inverted cone 14 having perforations all around its body part. This inverted cone 14 has a flange portion 15 which fits in the inside of the top 7 and has 55 L-shaped slots 16 adapted to inclose an in-

wardly projecting pin 17 to hold the cone 13 and the inverted perforated cone 14 in the position shown in Fig. 1. Holes 18, 18, etc., are formed in the top 9 so that the upper edge of the holes come slightly below the upper edge of the curved flange portion 8.

In operation, air is supplied to the burner 4 through the holes 18, 18, etc., flowing upwardly and over the edge of the curved flange 8, thence downwardly through the perforations 19, 19, etc., in the inverted cone 14, thence down on the inside of the lantern to the burners to supply sufficient air for proper combustion in the flame. The heat 70 and products of combustion rise through the cone 13 and the space 20, thence outwardly, being carried out by cross drafts over the top of the cone 13 and under the canopy 21. In case of a strong side current or gust of 75 wind striking the cone 9, passing through the holes 18, 18, etc., it would strike the side of the inwardly curved flange 8, be deflected upwardly, as shown by the arrows, and pass out through the holes 12, 12, etc., to 80 the spaces 20 under the canopy 21, and be carried out by the cross drafts of air over the top of the cone 13. This construction effectively prevents strong currents of air 85 and gusts from passing down through the holes 19, 19, etc., in the cone 14 to the interior of the lantern or lamp.

The form of the cones and the manner of attaching them together may be somewhat changed without departing from the spirit 90 of my invention.

What I claim is—

1. In a lantern, a body casing having an air chamber in its top consisting of an inner imperforate tube and an outer casing having holes mid-way of its height; a perforated plate at the top of the casing having an inner hole to receive the top of the imperforate tube; an outwardly and upwardly flaring perforated closure at the bottom of 95 the air chamber secured to the lower end of the imperforate tube; means for securing the upper end of the perforated flaring closure to the outer casing; and an inwardly and upwardly curving portion extending 100 upwardly to approximately the top of the holes in the middle portion of the outer casing.

2. In a lantern, a body casing having an air chamber formed in its upper portion by 110

means of an inner imperforate tube and the outer casing of the body, the outer casing having holes approximately mid-way the height of said air chamber; a perforated closure at the top of said air chamber; an outwardly and upwardly flaring perforated closure at the bottom of said air chamber secured to the bottom part of the inner imperforate tube and to the outer casing; and 10 an inwardly and upwardly curving wall ex-

tending to approximately the top of the holes mid-way the outer casing.

In testimony whereof, I have hereunto set my hand, in the presence of two subscribing witness, this the 15th day of September, A. D. 1908.

CHARLES C. BRIAND.
